UNITED STATES PATENT OFFICE.

GEORGE F. READ, OF NEW YORK, N. Y.; ASSIGNOR TO ROBERT HOE, THEODORE H. MEAD, AND CHARLES W. CARPENTER, OF SAME PLACE.

WEB-CUTTING MECHANISM.

SPECIFICATION forming part of Letters Patent No. 608,624, dated August 9, 1898.

Application filed April 21, 1896. Serial No. 588,444. (No model.)

To all whom it may concern:

Be it known that I, GEORGE F. READ, a citizen of the United States, residing at New York, (Brooklyn,) county of Kings, and State 5 of New York, have invented certain new and useful Improvements in Web-Cutting Mechanism, fully described and represented in the following specification and the accompanying drawings, forming a part of the same.

These improvements relate to means for cutting webs of material into sheets and delivering the same, being especially designed for use as a delivery mechanism of that class 10 of printing-machines which print long lengths or webs of paper required to be severed into short lengths or sheets, which sheets are to be delivered either singly or with two or more associated and in either case folded or flat.

In the accompanying drawings, Figure 1 20 represents so much of a side elevation of a printing-machine as is necessary to illustrate the practical use of these improvements. Fig. 2 is an enlarged sectional elevation of the group of associated carriers A B C in 25 which these improvements are embodied. Fig. 3 is an enlarged plan view of said carriers, the central portions of which are removed to accommodate the proportions of the view. Figs. 4, 5, 6, and 7 are still more enlarged sectional views of portions of the carriers A B, showing the mechanisms thereof in different positions of their operative movements.

These improvements are shown herein as 35 embodied in a web-perfected printing-machine, which will be generally described in order that the improvements may readily be understood.

In Fig. 1 is shown the last impression-cylinder I and last type-cylinder T of a web-perfected printing-machine, and the printed web W therefrom is shown as passing over guiding-rollers 50 60 70 to and between the rotating carriers A and B of a delivery mechanism, said delivering mechanism additionally having in this instance a delivering-cylinder C. As the invention is comprised within this delivery apparatus, no further description of the printing-machine is necessary, except to 45 say that it is a common construction in the art and may have substituted for it any other

web-printing machine the product of which is led to a delivery apparatus comprised of rotating carriers, as A B, and the improvements combined with them in the same manner or substantially as is hereinafter described in detail, said delivery mechanism having a delivery-cylinder C or any other means for disposing of the sheets produced by the mechanism embodying the improvements. 55

In order to provide for the continuous onward movement of a web of paper that is severed into sheets and the like continuous movement of the sheets severed therefrom, sheet-carrying pins have been provided to impale 60 the forward end of the sheets, and thus cause the onward movement of the web when a sheet has been severed therefrom, which forwarding-pins require no space between sheet and sheet for their engagement with the leading 65 end of such sheet length and enable said continuous onward movement to be performed; but at the present day, when fine work is required, especially in bookwork, the perforations made by these pins in the leading end of 70 the sheet are great objections, because they mar the work when the paper composing the sheet is entirely used or entail a loss by trimming the edges of the book in order to remove the parts containing these pin-holes, thus 75 causing a loss of material and additional expense to the work. To avoid these holes, a novel construction and arrangement of grippers 6 has been made, which will be best understood from Figs. 2 and 4 to 7, inclusive. 80

The rotating carrier A is preferably of such a size that it aids in the production of three sheets at each revolution, and it is, according to its size, provided with one, two, or more sets of grippers 6, each of which is mounted 85 on a rock-shaft 10, provided with a cross-head 11, one end of which is connected to a spring-rod 24, acting to hold the grippers closed, and the other end of which carries a stud or bowl contacting with cams X and Y, by which said 90 shaft is vibrated, as is common, to open and close said grippers. These grippers 6, however, are so shaped that they do not protrude beyond the periphery of the carrier A, but, on the contrary, make a sweep which is nearly coincident with the curved periphery of the carrier A, the center of their carrying-shaft 10 95 100

being directly under or in a radial line with the points of the grippers when closed, (see Fig. 2,) so that in opening the arc described by the points of the grippers will be within 5 the periphery of the cylinder, thus allowing the grippers 6 to be opened underneath the incoming web without puncturing or contacting with it. When closed, these grippers 6 press upon an angular-faced bearer 9, inclined 10 inwardly from the periphery of the carrier A, but so shaped between the gripper-points as to provide a space or cutting-slot 2, that will be bridged by the passing web. For coöperation with these grippers 6 the companion 15 carrier B, having a circumferential extent equal to that of two sheets, carries two sets of presser-fingers 7, each set of which is hung upon a rock-shaft 12, that is provided with a rock-arm 20, one end of which is attached to 20 a spring-rod 25, whereby the fingers are spring-seated, so that they are normally held inwardly or within the periphery of the carrier B, as in Fig. 4, and which shaft 12 has the other end of its rock-arm 20 provided with a stud or bowl, 25 whereby it is rocked to project the fingers into action by its contact with a stationary cam 21. As these presser-fingers 7 at times sweep within the peripheral line of the carrier A for co-operation with the grippers 6 and both are momentarily closed against the angular bearer 9, (see Fig. 2,) the grippers 6 have their outer ends recessed, as shown in Fig. 3, to provide for this conjoint action in holding 30 the end of the paper. The carrier A is of course provided with recesses, in which the grippers 6 and the fingers 7 may sweep. The carrier B is provided with a stationary projecting knife 13, furnished, as is usual, with a spring-seated or elastic presser-block 14, 35 (see Fig. 4,) which knife moves against said web and severs it by perforating that part of the web which bridges the space or cutting-slot 2 in the carrier A, and as the fingers sweep close to the blade 13 the presser-block 14 has recesses 5 to permit of this movement. 45

As the mechanisms embodying these improved sheet-carrying devices are provided with means for folding the sheets thus formed, the same will be described in order that the 50 delivery of the sheets as an entirety may be best explained in the description of the operation.

The carrier A is provided at points midway between the grippers 6 with rotative folding 55 or tucking blades 15, that are mounted upon rock-shafts 8, each provided with a rock-arm connected to a spring-rod 27, whereby said blades 15 are normally held within the carrier B, said shaft also having a rock-arm 16, that 60 contacts with a cam D, to cause said blade to vibrate or swing outward in performing the tucking or folding operation, as in Fig. 7. The carrier B is also provided with two sets of nipping-jaws. In each set there is a stationary jaw 3 and a movable jaw 17, the latter being carried by a rock-shaft that is provided with a cross-head 23, one end of which

is attached to a spring-rod 28, whereby the said movable jaw is normally held closed and its other end provided with a stud or bowl, whereby through contact with a stationary cam E is held open at the proper periods of time. (See Fig. 7.) The carrier C is provided with two sets of ordinary grippers 19, projecting from shafts 30, that carry cross-heads 18, one 70 end of which is attached to a spring-rod 29, whereby they are normally held closed, and the other end of which head carries a stud or bowl that contacts with a fixed cam F, whereby said grippers are properly opened to receive 75 the folded sheet from the nipping-jaws 17 and deliver the same. In this instance the carrier C has tapes 22 running around it and in contact with the carrier B, which tapes aid in the performance of the folding operation. 85

As the carriers rotate in unison and the grippers 6, carried by the carrier A, and the cutting-blade 13, carried by the carrier B, are approaching the point of nearest contact between these carriers (see Fig. 4) the web 90 W will be laid upon the periphery of the carrier A, overlying the cutting-slot 2 in the carrier A, the grippers 6 then standing open, but on the rear side of the web W, then stretched over them.

When the carriers A B have advanced these mechanisms to the position shown in Fig. 5, the spring-seated presser-block 14 will bear upon the paper web each side of the cutting-slot 2 in the carrier A and hold the web while 100 the cutting-blade 13 is forced through the same to sever a sheet's length therefrom as the carriers A B move onward. Simultaneously with this cutting action the fingers 7 are swung outwardly by the action of the 105 cam 21 on the rock-arm 20, thus pressing the front edge of the web W, then overlapping the angular bearer 9, as in Fig. 6, this action being slightly in advance of the closing movement of the grippers 6, caused by their rock-arm 11 descending onto the low part of the cam X, which gripper movement made, as before stated, in an arc that swings their points behind the web, seizing said web by bearing it against the angular face of the 115 bearer 9, the bifurcated ends of said grippers 6 moving past the projecting points of the fingers 7 and pressing the web end onto the bearer. This disposition of the grippers 120 6 is maintained long enough to carry the leading end of the web a half-sheet's length distant from the point where the web was severed, as in Fig. 7, whereupon said grippers are opened by the action of cam Y to release the end of the web (see dotted lines, Fig. 7) 125 simultaneously, or thereabout, with the rocking movement of the tucking-blade 15, caused by the high part of the cam D, which acts to tuck the middle transverse portion of the sheet into the recess in the carrier B, in which 130 the jaws 17 vibrate, which jaws make this movement by the action of the cam E in such manner as to receive the doubled or folded part formed by the tucking-blade 15 and allow

said blade to be removed therefrom and the sheet length to be clamped by said jaws 17, so that thereafter it will move with the carrier B, as is shown by the dotted lines in Fig. 5, and its tail end will be lapped upon the companion half of the sheet it partly forms.

The continued rotative movement of these carriers causes the folded sheet to be laid upon the carrier B, (see Fig. 2,) and it is 10 finally delivered therefrom in a manner too well understood to need any detailed description. When the cutting-blade and the fingers of the carrier B come into co-operative position with respect to the next set of grippers 15 6, the cutting operation is again performed, the leading end of the web is seized by the grippers 6, and the described folding and delivering operations are repeated. By this improved construction and operation of the 20 mechanisms the web is severed to divide it into sheet lengths without losing the continuity between sheet and sheet. The leading end of the web formed by the cutting operation and which otherwise would be free is not 25 only clamped to the cylinder A by the fingers 7, but this clamping of it is maintained for a period that will enable the rotative movement of the carrier B, supporting these fingers, to withdraw the cutting-knife out of the 30 carrier A, thus enabling the grippers 6 to unobstructedly make their sweeping movement in closing down upon the end of the sheet while it is held by the fingers 7 onto the carrier A and seize the same by clamping it to 35 the inclined face of the bearer 9. This accomplished, the fingers 7 are by the further rotative movement of the carrier B withdrawn from the end of the web, and it is then wholly controlled by the grippers 6. These grippers 40 are thus enabled to move in both directions without contact with the overlying paper or the cutting-blade 13, the web is positively and continuously held and moved onward, and the sheets are produced without any 45 abrasion of their leading ends either upon the surface or through the body thereof.

This invention is especially advantageous in that class of web-machines used for the production of books, magazines, and pamphlets and in which it is usual to associate two or more sheets together and fold them simultaneously. This association or collection of sheets is accomplished upon carrier A, which for convenience of illustration is shown 55 in Figs. 1 to 7 as arranged for collecting two sheets in manner similar to that described in Patent No. 197,700.

The cam D, which is pivoted at its lower end and operates the tucking-blades 15, is arranged so that it may be swung out of the path of the rock-arms 16 alternately by means of a connecting-rod 40, to which suitable reciprocations are imparted by means of a cam G, fast upon the shaft of carrier B, and the 65 cam Y, which opens the grippers 6, is also arranged so that it may be swung out of the path of rock-arms 11 alternately by a wrist-

pin 4 on the end of the shaft of carrier B and a connecting-rod attached to a rock-arm on the end of the shaft to which said cam Y is 70 attached. (See Fig. 1.)

By this arrangement the forward end of an incoming sheet will be clamped to the carrier A by the grippers 6 and carried around, but will neither be released by these grippers 75 upon its first revolution nor will the tucking-blade 15 be projected to fold it into the nip of the jaws 17, for their respective cams Y and D will have been during that revolution swung out of action; but upon the next revolution of carrier A, during which these cams resume their operative positions, a second sheet will be superimposed upon the first, the grippers 6 will open to receive its end, and though clamping it with the first to carrier A 85 will release both at the proper time for the tucking-blade 15 to tuck both sheets into the nip of the jaw 17, whereupon the two sheets will be folded off onto carrier B and be delivered by cylinder C. 90

Although an arrangement of the carriers suitable to the collection of two sheets is shown and is sufficient as illustrative of this operation, it is practicable to make the carrier A of such a size as to collect three or 95 more sheet lengths, as may be desired, by means substantially such as are described in the patent referred to.

The arms 36, projecting from the shaft 12, which also carries the presser-fingers, are not 100 essential, though they afford a convenient means for bridging the opening in the shell of the carrier B, which is a convenient construction to provide for the carriage of the tapes and yet aid access to the fingers for adjusting the same. As shown, they slightly rock with the shaft, but might be stationary, if desired.

What is claimed is—

1. The combination with a rotative carrier 110 provided with a cutting-blade and adjacent thereto with fingers having means for projecting them into contact with the end of the web to clamp the same against a bearing in the opposite carrier, of a companion rotative 115 carrier provided with vibrating grippers operating to bear upon and hold said inwardly-projecting web end within the periphery of the carrier, substantially as described.

2. The combination with two carriers, of 120 cutting mechanism, one member of which is carried by each carrier, fingers normally carried within the periphery of one of the carriers and projected therefrom to bend the leading end of the sheet or web immediately 125 after the same has been severed by the cutting mechanism within the periphery of the other carrier and lap the same upon a supporting-surface therein, and grippers sweeping within the peripheral line of said latter 130 carrier and operating to clamp said sheet or web onto said surface and carry it onward with the carrier, substantially as described.

3. The combination of the carrier A, its

- bearer and vibrating grippers coacting with said bearer and hung and vibrated so that their extremities swing within the peripheral line of the carrier, cutting mechanism, one member of which is carried by the carrier A, and carrier B carrying the other member of the cutting mechanism and having fingers normally carried within its periphery, and means for vibrating the same to lay the sheet end onto said bearer within said carrier A, substantially as described.
4. The combination with the carrier A having a cutting member, an inclined bearer and vibrating grippers hung and vibrated so that their extremities swing within the peripheral line of the carrier, of the carrier B, its cutting-blade and vibrating fingers the latter co-operating with said bearer in the carrier A to clamp the leading end of the sheet immediately behind the cutting-blade against the bearer, substantially as described.

5. The combination with the carriers A and B, the grippers 6 and the vibrating presser-fingers 7, of the block 14 having recesses 5, substantially as described. ²⁵

6. The combination with the carriers A and B, the grippers 6 and the presser-fingers 7, of the inclined bearer 9 and its recess 2 and a cutting-blade coöperating with said recess, substantially as described. ³⁰

7. The combination with the carriers A and B, the fingers 7 and cutting-blade 13, of the grippers 6 and block 9 having the recess 2 for coöperation with said blade, substantially as described. ³⁵

In testimony whereof I have hereunto set my hand in the presence of two subscribing witnesses.

GEORGE F. READ.
